(57) **CLAIM**

The ornamental design for a shoe sole, as shown and described.

DESCRIPTION

FIG. 1 is a left front perspective view of one embodiment of the present invention.

FIG. 2 is a left side elevational view of the embodiment shown in FIG. 1.

FIG. 3 is a right side elevational view of the embodiment shown in FIG. 1.

FIG. 4 is a front elevational view of the embodiment shown in FIG. 1.

FIG. 5 is a rear elevational view of the embodiment shown in FIG. 1; and,

FIG. 6 is a bottom view of the embodiment shown in FIG. 1.

The broken lines showing the shoe upper throughout the views illustrate the environment in which the design resides, and form no part of the claim. The broken lines shown on the forefoot of FIG. 6 represent an internal boundary, with the broken lines and the area within forming no part of the claim.
